UNITED STATES PATENT OFFICE.

GEORGE BARTON, OF EASTHAMPTON, MASSACHUSETTS, ASSIGNOR TO H. W. BUTTERWORTH & SONS COMPANY, A CORPORATION OF PENNSYLVANIA.

CLOTH-GUIDING DEVICE FOR TEXTILE-MACHINES.

1,312,153.

Specification of Letters Patent. Patented Aug. 5, 1919.

Application filed February 7, 1918. Serial No. 215,818.

To all whom it may concern:

Be it known that I, GEORGE BARTON, a citizen of the United States, and resident of Easthampton, county of Hampden, and 5 State of Massachusetts, have invented an Improvement in Cloth-Guiding Devices for Textile-Machines, of which the following is a specification.

My invention has for an object the guiding 10 of cloth to textile machines which are intended to manipulate and stretch the cloth such as is accomplished in tentering machines, by way of example, whereby the cloth is properly delivered to the cloth 15 clamps on the machine in an effective and positive manner to insure the desired action while in the custody of the tentering machine.

Heretofore in practice considerable difficulty 20 has been found in attempts to feed the selvages of a fabric to the cloth clamps of the reciprocating frames of a tentering machine, in that the said frames are so supported that during their 25 reciprocation they alternately approach and recede from each other, varying the transverse width apart of the two chains of cloth clamps. It is therefore the object of my invention to provide an effective feeding 30 mechanism for the cloth which shall impart to it transverse oscillations commensurate with the reciprocations of the tentering frames and which shall maintain the selvages in proper alignment with the cloth 35 clamps of the respective frames.

My object is further to provide automatic 40 means for acting upon the selvages of the fabric and controlled by the lateral positions of the selavage edges to cause the cloth to be more or less stretched as to width and positioned transversely, whereby it is accurately guided into the cloth clamps at each side of the machine, with the result 45 that the said clamps shall grip the fabric adjacent to the selvages thereof with accuracy for the better manipulation of the fabric during its stretching and working while being conveyed along the length of the tentering machine.

50 My invention also consists of improvements hereinafter described whereby the above objects and results are attained, said improvements comprising certain organization and combination of parts which are

fully described hereinafter and more particularly defined in the claims. 55

For the purpose of illustrating my invention, I have shown in the accompanying drawings the embodiment thereof which is at present preferred by me, since the same 60 is in form to give satisfactory and reliable results, but it is to be understood that the several instrumentalities of which my invention consists, can be variously arranged and organized and that my invention is not 65 limited to the precise arrangement and organization of the instrumentalities herein shown and described.

Referring to the drawings:—Fig. 1 is a 70 plan view showing my improved cloth guiding means as applied to the receiving end of a tentering machine; Fig. 2 is a side elevation of the same; Fig. 3 is an elevation, with part in section, showing a portion of my improved guiding means on a larger 75 scale; Fig. 4 is a front elevation of the same; and Fig. 5 is a plan view of the construction shown in Fig. 4.

2, 2, illustrate the receiving ends of the longitudinal frames of a tentering machine. 80 These frames are supported at numerous places along their length by means of horizontal frames 3 journaled at their centers 4 upon suitable standards 4^a and having their outer ends journaled at 3^a to the under 85 side of the frames 2, 2, whereby the said frames are supported and permitted to have longitudinal reciprocation simultaneously in opposite directions. The oscillation of the supporting frames 3 causes the longitudinal 90 frames 2, 2, not only to reciprocate in opposite directions, but to approach and recede from each other alternately during such longitudinal reciprocations, all of which is well known in connection with tentering 95 machines. Tentering machines are commonly provided with a transverse screw shaft 5 which permits relative adjustment of the frames 2, 2, toward or from each other to suit fabrics of different widths, but such provision need not be specially considered 100 as this is a common expedient in tentering machines. 6 represents chains, and 7 cloth clamps formed thereon. Ordinarily, each link of the chain is provided with a cloth 105 clamp so that these chains in reality constitute chains of cloth clamps, and they are guided longitudinally along the frames 2

and about the guide wheels 6^a at the receiving end of the tentering machine. Suitable means is also provided at this end for putting the chains under tension but such 5 tails need not be considered as it is a usual construction of tentering machines. While the cloth clamps are conveyed around the guide wheels 6^a, the gripping jaws of the clamps are automatically opened by contact with the rim of the wheel 7^a which is supported and journaled concentrically with the axis of the guide wheels 6^a. In this 10 manner the cloth clamps are opened automatically at the receiving end of the tentering frames so as to receive the selvages of the fabric and immediately thereafter grip them. I will now proceed to describe in detail my improvements which are applied to the receiving ends of the reciprocating 15 frames 2, 2, of the tentering machine.

To the end of each of the reciprocating frames 2, 2, I secure a bracket 8 which is provided with vertical bearings 9, 9, in which a vertical shaft 20 is journaled. Secured rigidly to the top of the shaft 20 is a horizontal bearing 11, and similarly secured to the extreme bottom of the shaft 20 is a horizontal bearing 12. The bearings 11 and 12 are parallel. There are similar vertical shafts 20 and bearings 11 and 12 in connection with the brackets 8 of each of the tentering frames. 13 is a horizontal shaft which extends through the bearings 11 at each side of the machine, and at one 25 side the shaft is held against longitudinal adjustment by collars 14 on the opposite sides of the bearing 11, said collars being secured in position by being pinned to the shaft (Fig. 4). The other end of the shaft 30 loosely extends through the bearing 11 of the other tentering frame. Parallel to the shaft 13 and journaled in the bearings 12 at each side of the machine, is a second shaft 15, and similarly this shaft is held against 35 longitudinal movement by similar collars 14 pinned to it and arranged upon each side of one of the bearings 12. The other end of the shaft 15 is loosely held in the other bearing 12 as in the case of the shaft 13. 40 It will now be seen that as the two frames 2, 2, reciprocate, the shafts 13 and 15 will be oscillated corresponding to the oscillating frame 3, and the changes in position of these frames 2, 2, toward and from each 45 other during the oscillations will be compensated for by the shafts 13 and 15 sliding longitudinally through one set of the bearings 11 and 12, as will be more clearly understood by examination of Fig. 1. The shafts 50 13 and 15 may be free to rotate but this is not essential, as they may be simply smooth guides over which the cloth is guided as indicated. It will be noted that when the oscillations of the shafts 13 and 15 take 55 place, they will necessarily rock the vertical

shafts 20, and this rocking of the vertical shafts provides means for rocking the guider devices which position the selvages correctly to insure their being properly received by the cloth clamps.

70

I will now describe the cloth feeders which definitely position the fabric so that the lateral or selvage edges thereof are accurately delivered to the cloth clamps. Each of the vertical shafts 20 is provided with a 75 guider 19, and these latter project inwardly toward the cloth in opposite directions, but in all material respects their relation to and action upon the cloth is the same, and it will suffice to describe in detail one of these devices. Secured to the shaft 20 between the two bearings 9, 9, of the bracket, is a sleeve 16 fastened in position upon the shaft by means of set screws 17. This sleeve 16 is provided with a horizontal hub 16^a through 80 which a horizontal adjustable rod 21 extends, said shaft being adapted to be secured in adjusted position by means of the set screw 22. The end of the rod 21 adjacent to the cloth has hinged to it at 24 the 85 guider frame 23 so that this frame may be adjusted in a vertical plane, and at the same time may be adjusted transversely of the cloth by the longitudinal adjustment of the rod 21. It is manifest that this adjustable 90 mechanism for the guider frame gives capacity for universal adjustment. The guider frame 23 is provided with the two guide surfaces 25 over which the cloth travels. Journaled to the guider frame 23 in front 95 of these guide surfaces 25 is a roller 26 between which and the guide surfaces the fabric passes. 27 is a guider roller which is movable to or from the roller 26, and is arranged upon the opposite side of the 100 fabric so that the fabric is pinched between the two rollers when the roller 27 is moved toward the roller 26. The roller 27 is journaled in a hinged frame 28 carried by the guider frame, and this frame is operated 105 by a suitable motor device 28^a controlled by a valve 29 operated by a suitable trip device 30 which provides an arm 30^a which extends upward through a slot in the guider plate 25 in position to be acted upon by the selvage of 110 the cloth. In operation, the motor device is actuated by compressed air to move the roller 27 toward the roller 26, and the time of action of this motor device is regulated by the valve under the control of the fabric. 115 It will further be observed that the guider frame is adjusted obliquely to the rod 21 so that the rollers 26 and 27 are arranged at an oblique angle, such that when the fabric is pinched between the two rollers 26 and 27, 120 its upward movement will tend to shift the fabric laterally toward the control arm or finger 30^a and toward the cloth clamps. The fabric in traveling upward is caused to act upon the controlling finger 30^a and when 125 130

the same is moved to the left (Fig. 4), the air pressure is exhausted from the motor to relieve the pressure from the roller 27 to arrest further lateral movement of the selvage of the fabric. Should the selvage tend to move to the right (Fig. 4), it will be followed by the finger 30^a, and this will, through the valve, supply pressure to the motor and cause the roller 27 to apply pressure to the fabric and thereupon through the oblique arrangement of the rollers, the selvage of the fabric will tend to once more move to the left. In this manner, the selvage is guided accurately between very slight variations into the cloth clamps 7 of the tenter frame so that it is properly gripped by said clamps. The particular details of the motor devices for operating the guiders are immaterial to the present invention, but the preferred construction which is employed by me is that which is shown in the patent granted to H. C. Brehmer on December 8, 1914, and numbered 1,120,019.

It will be understood that the guiders operate on each selvage of the fabric in an independent manner, but the total width of the fabric when in a reasonably stretched condition should just equal the normal distance between the two control fingers 30^a of the feeders, and thereafter the fabric might be considered as shifting bodily slightly from one side or the other, or stretched by action at one selvage or the other, so as to properly be fed to both sets of cloth clamps 7 on the two tenter frames. Even if the cloth, passing over the guide shafts 13 and 15, should be more or less loose as to width, the guiders 19 will accurately control the selvages into proper alinement with the cloth clamps, and it will therefore be seen that each guider 19 directly coöperates with its particular associated cloth clamps and tenter frame for laterally positioning the cloth selvage, but both of the guiders 19 and the oscillating rods 13 and 15 coöperate in conjunction with taking care of the fabric being fed to the tenter machine and causing it to oscillate in conformity with the oscillations produced upon the fabric in the custody of the cloth clamps of the tenter machine itself, whereby at all times the fabric is properly fed to the machine and without putting any undue strain upon it at its point of delivery into the cloth clamps. After it has once been gripped by the cloth clamps, the fabric may then be subjected to the various complex stretching operations which are insured by the action of the tenter machine.

I have found it desirable that two transverse guide shafts 13 and 15 be employed, one above and the other below the guiders 19, but I do not restrict myself to the use of the lower shaft 15 as this shaft may be omitted if the cloth is properly guided from near the floor. Furthermore, it is to be under-

stood that while it is desirable to feed the cloth upward so that the normal gravity action of the cloth below the guiders may be utilized, I do not limit myself to this particular arrangement as the parts may be suitably arranged to permit the cloth to be delivered to the transverse guide shaft 13 from the direction found most convenient and suitable. The more essential feature of my invention when applied to tentering machines, resides in the oscillating shaft 13 moved under the action of the reciprocating tenter frames, and combined with mechanism for oscillating feeders in conjunction with the shaft, but it is to be understood that my improvements are not restricted to the particular character of the machine to treat the fabric after the cloth has been once delivered to the cloth clamps.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:

1. In an apparatus of the character stated, oppositely reciprocating longitudinal frames provided with cloth clamps, in combination with a transverse guide shaft extending across the receiving end of the apparatus and of a width greater than the distance between the cloth clamps of the two frames and arranged in horizontal alinement with the clamps, suitable means for supporting and oscillating the guide shaft horizontally with movements to correspond to and in timed relation with the relative reciprocations of the frames and their clamps, and guider devices arranged to oscillate commensurately with the oscillations of the transverse shaft for stretching and guiding the fabric passing over the guide shaft to the clamps whereby its selvages may be spread and laterally positioned to insure proper delivery into the clamps.

2. In an apparatus of the character stated, oppositely reciprocating longitudinal frames provided with cloth clamps, in combination with a transverse guide shaft extending across the receiving end of the apparatus and of a width greater than the distance between the cloth clamps of the two frames and arranged in horizontal alinement with the clamps, suitable means for supporting and oscillating the guide shaft horizontally with movements to correspond to and in

timed relation with the relative reciprocations of the frames and their clamps, guider devices arranged to oscillate commensurately with the oscillations of the transverse shaft 5 for stretching and guiding the fabric passing over the guide shaft to the clamps whereby its selvages may be spread and laterally positioned to insure proper delivery into the clamps, and means for adjusting the 10 guiders relatively nearer or farther apart to suit different widths of fabric to be handled.

3. In an apparatus of the character stated, oppositely reciprocating longitudinal frames 15 provided with cloth clamps, in combination with a transverse guide shaft extending across the receiving end of the apparatus and of a width greater than the distance between the cloth clamps of the two frames 20 and arranged in horizontal alinement with the clamps, suitable means for supporting and oscillating the guide shaft horizontally with movements to correspond to and in timed relation with the relative reciprocations 25 of the frames and their clamps, guider devices arranged to oscillate commensurately with the oscillations of the transverse shaft for stretching and guiding the fabric passing over the guide shaft to the clamps whereby 30 its selvages may be spread and laterally positioned to insure proper delivery into the clamps, and means for changing the angle of the guiders relatively to the transverse guide shaft while maintaining their oscillatory relation with the guide shaft.

4. In an apparatus of the character stated, oppositely reciprocating longitudinal frames provided with cloth clamps, in combination with a transverse guide shaft extending 40 across the receiving end of the apparatus and of a width greater than the distance between the cloth clamps of the two frames and arranged in horizontal alinement with the clamps, a second transverse oscillating guide shaft arranged at a different elevation 45 to the first mentioned guide shaft and oscillating simultaneously thereto, suitable means for supporting and oscillating the guide shafts horizontally with movements to 50 correspond to and in timed relation with the relative reciprocations of the frames and their clamps, and guider devices between the two transverse oscillating shafts arranged to oscillate commensurately with the oscillations 55 of the transverse shafts for stretching and guiding the fabric passing over the guide shafts to the clamps whereby its selvages may be spread and laterally positioned to insure proper delivery into the clamps.

6. In an apparatus of the character stated, the combination of two reciprocating frames and their cloth clamps, with means to reciprocate the frames simultaneously in opposite directions, a vertical shaft arranged at the 60 receiving end of each of the reciprocating

frames, a transverse guide shaft having a connection with the vertical shafts so that when the longitudinal frames reciprocate the transverse shaft is oscillated and rocks the vertical shaft, and guider devices secured to each of the vertical shafts and oscillated therewith whereby their oscillations maintain them in alinement during the reciprocations of the reciprocating frames, said guiders acting upon the fabric being delivered to the clamps to properly position the selvages thereof whereby they may be properly received by the clamps.

6. In an apparatus of the character stated, the combination of two reciprocating frames 80 and their cloth clamps, with means to reciprocate the frames simultaneously in opposite directions, a vertical shaft arranged at the receiving end of each of the reciprocating frames, a transverse guide shaft having a 85 connection with the vertical shafts so that when the longitudinal frames reciprocate the transverse shaft is oscillated and rocks the vertical shaft, guider devices secured to each of the vertical shafts and oscillated 90 therewith whereby their oscillations maintain them in alinement during the reciprocations of the reciprocating frames, said guiders acting upon the fabric being delivered to the clamps to properly position the selvages 95 thereof whereby they may be properly received by the clamps, and means for adjusting the longitudinal frames and the guiders nearer or farther apart while maintaining the connection of the transverse shaft with 100 the two vertical shafts.

7. In an apparatus of the character stated, the combination of two longitudinal oppositely reciprocating frames and cloth clamps carried thereby, with means for guiding a 105 web of cloth to the cloth clamps, said means comprising a vertical shaft journaled adjacent to the receiving ends of the respective frames, means for imparting to said shafts reciprocating motions to maintain them in 110 substantially the same relative position to the reciprocating frames while being reciprocated, a transverse guide shaft forming a connection between the vertical shafts whereby they are both simultaneously rocked about 115 their vertical axes, and a guider device secured to each of the vertical rocking shafts, said guiders directed toward each other and respectively hinged so as to be adjustable in a plane through the transverse guide shaft 120 whereby they may be adjusted to or from said shaft to change their obliquity to the length of the cloth being fed over the guide shaft.

8. In an apparatus of the character stated, the combination of two longitudinal oppositely reciprocating frames and cloth clamps carried thereby, with means for guiding a web of cloth to the cloth clamps, said means comprising a vertical shaft journaled adjacent to the receiving ends of the respective 125 frames, a transverse guide shaft having a 130

frames, means for imparting to said shafts reciprocating motions to maintain them in substantially the same relative position to the reciprocating frames while being reciprocated, a transverse guide shaft forming a connection between the vertical shafts whereby they are both simultaneously rocked about their vertical axes, a guider device secured to each of the vertical rocking shafts, said guiders directed toward each other and respectively hinged so as to be adjustable in a plane through the transverse guide shaft whereby they may be adjusted to or from said shaft to change their obliquity to the length of the cloth being fed over the guide shaft, and means to adjust the guiders relatively to their vertical shafts whereby they may be adjusted relatively to or from each other without changing the relative adjustment of the vertical shafts.

9. In an apparatus of the character stated, the combination of two longitudinally oppositely reciprocating frames and cloth clamps carried thereby, with means for guiding a web of cloth to the cloth clamps, said means comprising a vertical shaft journaled adjacent to the receiving ends of the respective frames, means for imparting to said shafts reciprocating motions to maintain them in substantially the same relative position to the reciprocating frames while being reciprocated, a transverse guide shaft forming a connection between the vertical shafts whereby they are both simultaneously rocked about their vertical axes, a guider device secured to each of the vertical rocking shafts, said guiders directed toward each other, and means to adjust the guiders, relatively to their vertical shafts whereby they may be adjusted relatively to or from each other without changing the relative adjustment of the vertical shafts.

10. In an apparatus of the character stated, the combination of two longitudinally recip-

rocating frames and their clamps, brackets secured to said frames at their receiving ends, vertical shafts journaled in said brackets, two transverse shafts connecting the two vertical shafts and causing them to rock in the bracket commensurately with the opposite reciprocations of the longitudinal frames said shafts one above the other, suitable frames secured to the vertical shafts and sustained by the brackets, and independent guiders secured to the suitable frames and positioned intermediate of the upper and lower transverse shafts for operating upon the cloth adjacent to the selvages thereof while being guided over the oscillating transverse shafts.

11. In an apparatus of the character stated, the combination of two longitudinally reciprocating frames and their clamps, brackets secured to said frames at their receiving ends, vertical shafts journaled in said brackets, two transverse shafts connecting the two vertical shafts and causing them to rock in the bracket commensurately with the opposite reciprocations of the longitudinal frames said shafts one above the other, suitable frames secured to the vertical shafts and sustained by the brackets, independent guiders secured to the suitable frames and positioned intermediate of the upper and lower transverse shafts for operating upon the cloth adjacent to the selvages thereof while being guided over the oscillating transverse shafts, and means for adjusting the guiders transversely upon the suitable supports and also as to obliquity in the plane of the transverse and vertical shafts.

In testimony of which invention, I hereunto set my hand.

GEORGE BARTON.
